CLAIM

The ornamental design for a motorcycle facial mask, as shown and described.

DESCRIPTION

FIG. 1 is a perspective view of a motorcycle facial mask showing my new design;

FIG. 2 is a front elevational view thereof;

FIG. 3 is a top plan view thereof;

FIG. 4 is a bottom plan view thereof;

FIG. 5 is a side elevational view thereof, the opposite side being a mirror image; and,

FIG. 6 is a rear elevational view thereof.

The features shown in broken lines in FIG. 1 are shown for illustrative purpose only and form no part of the claimed design.
